CONTACTOR HEAD.

William M. Magers, Coon Rapids, and Palmer G. Wermager, Arthur G. Blomquist, and Ludolph Larsen, Minneapolis, Minn., assignors, by mesne assignments, to the United States of America as represented by the Secretary of the Navy

Original application Feb. 19, 1962, Ser. No. 174,325. Divided and this application Dec. 31, 1962, Ser. No. 248,823.

1 Claim. (Cl. 339—64)

The present invention relates to an electrical contactor head, and more particularly to a contactor head which will establish electrical circuitry under adverse environmental conditions.

This application is a division of application Serial Number 174,325, filed February 19, 1962 for Booster Contactor.

In the field of electrical connectors many attempts have been made to provide a connector which is capable of mating with a female connector even though there may be some misalignment between the male and female connectors. However, these attempts to solve the problem have not provided a satisfactory solution to all the problems in this area.

An object of the present invention is the provision of an electrical connector which is well constructed, easy to manufacture and is provided with elements that are capable of ready replacement.

Another object is to provide a connector having connecting pins that are substantially self centering.

A further object of the invention is the provision of electrical leads which will withstand considerable vibration.

Still another object is to provide connecting pins that will yield individually should the need arise.

A further object is to provide a multiple connector which is adapted for quick connection and disconnection.

Other objects and many of the attendant advantages of this invention will be readily appreciated as the same becomes better understood by reference to the following detailed description when considered in connection with the accompanying drawings wherein:

FIG. 1 is a vertical elevation of the contactor head illustrating the separation of the receptacle assembly from the plug assembly;

FIG. 2 is a sectional view of the receptacle assembly taken on the line 2—2 of FIG. 1;

FIG. 3 is an underside view of the receptacle assembly taken on the line 3—3 of FIG. 1;

FIG. 4 is a top view of the plug assembly taken on the line 4—4 of FIG. 1;

FIG. 5 is a bottom view of the plug assembly as indicated by the arrows 5—5 of FIG. 1;

FIG. 6 is an enlarged vertical section view of the assembled contactor head taken along the line 6—6 of FIG. 5 and showing a receptacle connector in phantom; and

FIG. 7 is a cross section taken on the line 7—7 of FIG. 6.

Referring now to the drawings, wherein like reference characters designate like or corresponding parts throughout the several views, there is shown in FIG. 1, which illustrates a preferred embodiment of the invention, a contactor constructed of two mating parts, a plug assembly 90 and a receptacle assembly 92. Thus the plug assembly 90 having a plurality of contact points 38 can readily be replaced if the latter become damaged or worn and require replacement.

As best shown in FIGS. 4, 5 and 6, the plug assembly 90 of the contactor head 10 consists of a cylindrical plug body 94 of insulating material that is slightly resilient. Any suitable type may be used. A plurality of cylindri-

2

cal cavities or bores 96, one for each contact point 38 are formed in this plug body 94. The cavities 96 are parallel to the axis of the plug body 94. Each cavity 96 is counterbored to provide a shoulder 98 and spaced beneath the shoulder 98 is a locking groove 100 formed in the counterbore wall.

The contact points 38 are the lower-most portions of electrically conductive plungers 102 which work within the cavities 96. The top end of each plunger 102 is formed with a spring centering boss 104 having a lower flange 106. The lower end consists of a slender shaft 108 which extends to the contact point 38.

A coiled spring 112 is seated in compression in the upper end of cavity 96 and against the flange 106 urging it downwardly against the upper flange 116 of an apertured eyelet type insert 114. The insert 114 is retained against the previously mentioned counterbored shoulder 98 by means of a retaining ring 120 which snaps into the retaining ring groove 100.

20 A lower flange 118 of insert 114 receives a flange 124 of a soft rubber cup-shaped boot 122 which fits closely within the lower portion of the cavity 96 flush with the bottom surface of the plug body 94. Insert 114 is provided with a bore 115 which is centrally located and extends the entire length of insert 114. It is through bore 115 that the shaft 108 of the plunger 102 extends. It is to be noted that a reasonable amount of clearance is present between the bore 115 and shaft 108, in addition, the bore 115 tapers outwardly at 117. The purpose of these

25 features is to permit each pin 38 to individually align itself with the mating member should there be some misalignment between a particular contact point 38 and the aperture which is to receive this particular contact point 38. Inasmuch as the plug body 94 is made of material which is slightly resilient the flange 106 will force the material to yield sufficiently to permit contact point 38 to enter its aperture. The boot 122 is apertured at the bottom thereof and is received at this point in a sealing groove 110 on the shaft 108.

30 As an alternative to the above recited male-female connection, the connectors that pins 38 enter into may be lead connectors, as shown in broken lines in FIG. 6 and designated LC. By having the connectors which pins 38 mate with made of lead or some other soft conducting material the problem of alignment becomes obviated. Since the lead is soft, pins 38 are not confronted with the problem of aligning itself with a particular hole. Pins 38 need only engage the lead connector and when the contactor head 10 is lowered into position pins 38 will form their own apertures in the lead.

35 Centrally located contact point 38 of the plug assembly has its plunger 102 electrically attached to a tubular plug pin 130 by means of a soldered-in connecting lead 128. The upper end of lead 128 extends through an aperture 127 in plug body 94. Connecting lead 128 is provided with a coiled portion 126 intermediate its ends. The coiled portion 126 absorbs the vibration and aligning that may be required of the contact pin 38. This plug pin 130 is inserted into a pin spacing insulating disc 148 of insulating material along with a plurality of L-shaped plug pins 138 and 140 forming an inner and outer circular array, respectively.

40 Horizontal legs 142 and 144 of the pins 138 and 140, respectively, extend radially from the underside of the insulating disc 148 between the radial barriers 150 formed therein as best shown in FIG. 7. The legs 142 and 144 of the pins 138 and 140, respectively, lie in potting compound 183 in a recessed well 132 of the body 94 and are formed with bifurcated ends 146. These ends 146 embrace and are soldered to short vertical portions 136 of coiled leads 134 which are disposed in the cavities 96 of the body 94. The coiled leads 134, in turn, are each at-

tached to the spring centering boss 104 of one of the plungers 102 of the remaining contact points 38.

The receptacle assembly 92, to which the above described plug assembly 90 mates, consists of an annular receptacle body 158 having a mounting flange 160 as shown in FIGS. 1, 2, 3 and 6. This flange 160 is provided with mounting holes 162 by which it may be bolted to any desired type of supporting device.

In the central bore 168 of the receptacle body 158, an insulating insert 170, as shown in FIG. 6, is supported by a flange 172. A plurality of shouldered female terminals 174, one for each pin 138 and 140 and also central plug pin 139, are positioned in holes formed in this insert 170. A terminal retaining disc 176 rests on top of the insert 170 in a counterbore 178 of central bore 168. Pin 180 extends through an aperture 179 in the sidewall thereof into the disc 176 thus holding it in position.

The upper ends of the terminals 174 are attached to the above mentioned leads 36. These are protected by a potting cap 182 having a flange 184 which snaps into a groove 186 of the receptacle body central bore 168 and is filled with an epoxy potting compound 188.

The plug assembly 90 and the receptacle assembly 92 are assured of correct mating by means of an indexing hole 156 in the former and an indexing pin 166 in the latter. Securing cap screws 154 passed through counterbored apertures 152 of the body 94 into threaded holes 164 of the receptacle 92 are conveniently accessible from the contact point side of the plug assembly 90 should the necessity arise for replacement of the latter.

In order to more completely describe the invention a brief description of its assembly follows:

Assuming that each of the major components, plug assembly 90 and receptacle assembly 92, have had their various components assembled, the assemblies 90 and 92 can be mated by aligning the indexing pin 166 with the aperture 156 and moving the lower face of mounting flange 160 into contact with the upper face of the plug body 94. As this is accomplished, the pins 138 and 140 are inserted into the female terminals 174. After this is done, the only remaining thing to be done is to insert bolts 154 into their respective apertures 164 and take up on the bolts until the plug assembly 90 and receptacle assembly 92 are securely brought into close engagement. Should there be any misalignment of a contact pin 38 with the aperture in contactor C which it is to mate, with a slight shifting of the contactor head 10, prior to the insertion of bolts 154, in one direction or another will force the pin to align itself with the aperture and thus permit the contact pin 38 to enter. As pointed out earlier in the specification, in one embodiment of the invention, the plug body 90 is made of an insulating material 94 which is slightly resilient and will permit the plungers 102 to individually realign itself to improve its mating capability.

Obviously many modifications and variations of the present invention are possible in light of the above teachings. It is, therefore, to be understood that within the scope of the appended claim the invention may be practiced otherwise than as specifically described.

What is claimed is:

In a contactor head having a plug section and a receptacle section adapted for mutual engagement, the com-

bination comprising; a receptacle body, a cap for enclosing the upper end of said body, said receptacle body having a flange portion at its lower end, said receptacle having a recess centrally located therein, an insert mounted within said recess, retaining means for holding said insert within said recess, a plurality of female terminals mounted in said insert, first lead means electrically connected to said female terminals and disposed to pass through said cap, a plug body, said plug body having a plurality of bores of uniform diameter terminating in a bore of lesser diameter, said bores being arranged in outer and inner concentric circles about a centrally disposed bore, said plug body having a recessed well in its upper face, a circular disc centrally disposed in said well for abutting said insert in the lower end of said receptacle body, said disc having a plurality of apertures therein for alignment with said female terminals, radially disposed longitudinal legs attached to said disc for supporting said disc within said recessed well, male terminal means disposed in said apertures of said disc for insertion into said female terminals, second lead means electrically connected to said male terminals and extending to the intersection of said recessed well and said bores, said recessed well being filled with a potting compound, an apertured insert disposed in each of said bores, said insert having a flange at either end thereof, each of said bores having a circumferential groove therein, a retaining ring disposed in said groove for abutting the flange on the upper end of said apertured insert to retain said apertured insert in said bore, a plunger disposed in each of said bores, said plunger having a shaft extending through said apertured insert, a spring supporting flange secured to the upper end of each of said shafts and disposed in abutting relationship with the upper end of said apertured insert, a spring disposed within each of said bores in abutting relationship with the upper end of each of said bores at one end thereof and in abutting relationship with said spring supporting flange at the other end thereof, a spring centering boss disposed within each spring and secured to said spring supporting flange, a coiled flexible electrical lead disposed within each of said springs for interconnecting the respective said second lead means with the respective plungers, each of said plungers terminating in a point and extending beyond the base of said plug body, a cuped-shaped boot disposed in sealing relationship within each of said bores, said boot having an upper flange which is inwardly directed and disposed about said apertured insert to secure said boot in said bore, said boot being secured in sealing relationship at the lower end thereof to said plunger, and means for aligning and fastening said receptacle body with said plug body.
